POINTER SIGHTING DEVICE

Emil Müller, Scheveningen, and Leopold Schmidt, The Hague, Netherlands, assignors, by mesne assignments, to Edgar William Brandt, Paris, France

Application April 5, 1927, Serial No. 181,200,
and in Germany October 6, 1926

6 Claims. (Cl. 33—49)

This invention relates to pointer sighting apparatus which may be used for guns adapted to swing about the usual training axis and an elevation or trunnion axis, as well as for guns in which 5 the gun barrel is adapted to swing about a third axis perpendicular to and intersecting the elevation or trunnion axis.

The main object of the invention is to provide apparatus of this character in which the mere 10 act of elevating the gun to bring an indicator controlled thereby into registry with another indicator controlled by adjustments of the sight in elevation causes deflection of a pointer laterally of the gun barrel to indicate the necessary 15 lateral adjustment of the gun barrel to correct for trunnion tilt, drift, displacement of target relative to the gun and other well known deflection corrections.

Other objects of the invention will appear as 20 the detailed description proceeds.

In the drawings,

Fig. 1 is an explanatory perspective diagram illustrating the general layout of the element of the gun and of parallelogram linkages controlled 25 by the setting of the sight and corresponding setting of the gun to effect the deflection indicating movements of a pointer relative to an indicator fixed to the gun barrel.

Fig. 2 is a side elevation of the sighting apparatus as applied to a gun, the supporting and 30 adjusting mechanism for the sight proper being shown in central vertical section and the gun being shown in horizontal position.

Fig. 2a is a side elevation of the sighting apparatus as applied to a gun, the several parts 35 of the sighting mechanism being shown in the positions assumed after adjustment of the gun in elevation.

Fig. 3 is a vertical transverse section taken on 40 the line 3—3 of Fig. 2 and illustrating the telescope and parts movable bodily therewith in elevation.

Fig. 4 is a plan view of the sighting apparatus, with the sight adjusting mechanism shown in 45 central horizontal section, part of a stop adjusting mechanism carried by a sight controlled pointer being broken away and shown in horizontal section.

Fig. 4a is a horizontal section on the line 4—4 50 of Fig. 3 but drawn to a larger scale than Fig. 4.

Fig. 5 is a fragmentary diagrammatic end elevation of the sight adjusting mechanism illustrating a flexible shaft and differential gear for adjusting the before mentioned stop.

Fig. 6 is a fragmentary detail of a modified

form of a pointer operating linkage used with the sighting mechanism disclosed herein when applied to guns rotatable about train and elevation axes only.

Fig. 7 is a fragmentary plan of the linkage 60 shown in Fig. 6.

In Fig. 1 there is diagrammatically illustrated a base *Bs*, which may be considered as a gun platform or deck, on which the gun carriage *Ca* is mounted to rotate about the train axis *y—y*. Standards *A1* and *A2* extend perpendicularly upward from said carriage *Ca* and are provided with the usual trunnion bearings for mounting the sleeve *Sl* rotatably about the elevation axis *x—x* perpendicular to and intersecting the train axis *y—y*.

The gun cradle *Cr* is mounted by suitable trunnions to pivot in the sleeve *Sl* about the axis *y'—y'*, which for convenience will be referred to hereafter as the pivot axis. For convenience of description, the axis *x—x* and *y—y* shall hereafter be referred to as the elevation axis and train axis, respectively.

A pointer *B2* is pivoted on the sleeve *Sl* to swing about the *y'—y'* axis, and is provided with an indicator *M2* adapted to cooperate with an index *B3* fixed on the gun *G* and carrying an indicator *M3* to indicate when the gun is properly laid to correct for lateral drift of the projectile, trunnion tilt, target velocity, etc.

The pointer *B2* is swung relative to *B3* by a system of parallelogram linkages controlled by the movements of the gun *G* in its adjustments to make an indicator of one said linkages register with an index controlled as to its movements by 90 the settings of the sight for elevation.

This system comprises a link *B1* fixedly secured to the trunnion *2* and held constantly parallel to a link *B* by means of a connecting link *b1* pivotally connected at its opposite ends to pivots *3* 95 and *4* extending laterally from link *B* and *B1* respectively and parallel to the trunnion axis *x—x*. The lower end of the link *B* is pivoted on a shaft *1* parallel to trunnion axis *x—x* and journaled in a bearing bracket *A* fixed to and extending rearwardly from the standard *A1*.

The distance between the axis of the shaft *C1* and the axis of pivot *3* is equal to that between the axis of the trunnion *2* and pivot *4*, and the distance between the axis of pivots *3* and *4* is equal to that between the axis of pivots *C1* and *2*, so that the link *B* is always maintained parallel to the link *B1* throughout all movements of the gun *G* about its elevation axis *x—x*.

The links B and B1 are bent over at their upper ends above the pivots 3 and 4, respectively, (see Fig. 3), and pivots 5 and 6 extend up from these upper ends to mount the links b2 and b3 for 5 swinging movement perpendicularly to the links B and B1 respectively. The link b3 forms one arm of a bell crank lever, the other arm b33 of which is connected pivotally at its end to a link b6 pivoted to the pointer B2 intermediate its 10 ends. (Fig. 4.)

The outer ends of the links b2 and b3 are pivotally connected to each other by ball and socket universal pivots 7 and 8, (see Fig. 3), at the opposite ends of a link b4, and the end of link 15 b2 extends beyond the ball 7 formed thereon to form stop b22, (Fig. 3), adapted to be held in yielding contact, by a tension spring b5, against a stop plate C3, (Fig. 3), adjustably mounted on the upper end of a sight controlled pointer C. 20 The tension spring b5 has its opposite ends suitably secured to links b1 and b4 so as to pull the link b4 toward the link b1 and thereby hold the stop b22 yieldingly against the stop plate C3.

The distance between the pivot axes 6 and 9, 25 (Fig. 4), is equal to that between the pivot axes 11 and 10; and the distances between pivot axes 6 and 11 is equal to that between the axes 9 and 10, so that the pointer B2 moves in parallelism with the arm b33 of the bell crank lever.

30 The sight controlled pointer arm C is rotatable about the pivot axis 1 and carries at its upper end the stop plate c3, (Fig. 3), in the path of movement of the stop b22, the plate c3 being adjustable for a purpose to be later described. 35 This sight controlled pointer arm has its upper end provided with an index M (Fig. 4) adapted to cooperate with an indicator M1 fixed on the downturned end of a stirrup St which is pinned at its other end to the top of pivot 5 and extends 40 over the link b2 and directly over the sight controlled pointer arm C.

The sight-controlled pointer C is first set by mechanism hereinafter described according to the desired elevation of the gun G. Then the 45 gun G is elevated by elevating gear, (described later), until the indicator M1 on the pointer stirrup St resists with the index M. When this occurs, the contact of stop b22 with the stop plate c3 causes the link b4 to rotate bell crank 50 arm b33 and link b6, (see Fig. 4), to move the pointer B2 in order to indicate the lateral adjustment of the gun G about its pivot axis y'-y' necessary to correct the laying of the gun for drift, trunnion tilt, etc.

55 The disclosure, so far, merely gives a general idea of the functions and operation of the deflection correcting linkages, the word "deflection" being used as a broad term to include all lateral corrections such as those necessary to compensate for trunnion tilt velocity and displacement of the target, etc. The sight adjusting mechanism will now be described in detail.

In Fig. 2 the main supporting and adjusting elements of the gun G are shown; the sight 60 adjusting mechanism and pointer control linkages are shown in full lines and with their parts in the position relative to the gun occupied by them when the gun is horizontal. Fig. 2a shows the same parts moved relatively to each other by 70 adjustment of the sight T, and by the corresponding elevation of the gun.

The gun carriage Ca, pivoted for rotation about the training axis y-y by suitable gearing has the standards A1 extending upwardly therefrom 75 and provided with bearings to receive rotatably

the trunnions 2, (only one of which is shown), extending laterally from the sleeve Sl in which the cradle Cr is mounted to swing about axis y'-y' by means of the pivots p and p1. The sleeve Sl has a gun elevating rack H suitably 80 fixed thereto; and an elevating gear H1 meshes with this rack to effect rotation of the sleeve Sl, and the gun G with it, about the trunnion axis x-x. To rotate the gun laterally of the sleeve Sl, the gun cradle Cr has bracket Br fixed thereto 85 and has its lower end provided with a gear W meshing with a worm S rotatably mounted in an arm W1 extending from the lower end of the sleeve Sl.

The specific details of the gun adjusting parts 90 shown and just described form no part of the present invention; but are herein described in order to make clear the operation of the sighting apparatus forming the real invention and connected thereto.

95 The sight adjusting mechanism is supported by a bracket A, (Figs. 2, 2a and 4), fixed to the standard A1 and is provided at its free end with a bearing A2 in which a hollow shaft a1 is journaled. A segmental worm gear a2 is keyed to the hollow shaft a1, and a worm a22 fixed to a shaft a3 having a hand wheel D1 at the end thereof which operates, through gear a2, to rotate the hollow shaft a1 in its bearing. The segment gear is enclosed by a cover Co having a 105 side wall Cs rotatable on the hub of the segment gear a2.

The link B is fixed to the wall Cs and therefore rotates freely about the axis 1 of the sight shaft C1 which is journaled in the hollow shaft 110 a1. This link B and the other links between it and the pointer B2 are identified by the reference characters applied to the corresponding links in Fig. 1, and is obviously designed to be rotated about the axis 1 of the sight shaft C1 by 115 the links B1 and b1 when the gun is rotated about its trunnion axis x-x.

A ring, (see Fig. 3), formed in two halves has one half D fixed to the hollow shaft a1 and has its other half D2 apertured to form a bearing 120 for the outer end of the sight shaft C1. A nut D3 screws onto the reduced end D4 of shaft C1 cooperates with the nut D5 at the other end of shaft C1 to lock the two halves D and D2 together and hold them assembled on the shaft C1 125 and hollow shaft a1. The shaft C1 has the sight controlled pointer C pinned thereto and interposed between the end of the bearing A2 and the nut D5.

The hollow shaft a1 has a segment gear a4 130 depending from the end thereof, (Figs. 2 and 3), with its teeth in mesh with a small segment gear a5 projecting laterally from the side of a larger segment gear e7 which is pivoted to swing about a bolt e77 which holds the lower ends of the 135 two halves of the ring gear together, with the hub e777 of gear e7 rotatable between said ends.

The shaft C1 where it projects from the inner end of hollow shaft a1, (see Fig. 4a), is cross-shaped and is bored perpendicularly to its axis 140 C1 to receive concentrically bored flanged bearing members 12 and 13 in which a shaft e1, having a worm e11 centrally secured thereto, is journaled.

The worm e11 meshes with the segment gear e7 145 and also with the gear E'', which is fixed to or formed integral with a tangent elevation member E on which the telescope standard T is mounted to rock about the pivot axis e10 normal to the shaft C1, (see Fig. 3). The member E 150

has its lower part formed as a comparatively wide ring R, (Figs. 2 and 3) which seats rotatably in an annular recess R₂, formed in the two halves d₃ of a two part bearing member which 5 seats on and straddles the upper parts of the ring members D and D₁.

The upper edge of the ring D—D₂ is provided with worm teeth t, and the bearing member d₃ has a shaft d₄ journaled therein and provided 10 centrally with a worm tw meshing with the teeth t in order to rotate the sighting telescope standard T bodily about the axis Z—Z (see Fig. 2) to compensate for trunnion tilt.

The two halves d₃ of the bearing member are 15 held together by means of the nut 14 at one end of the shaft d₄ and a hollow cap 15 pinned to said shaft d₄, the nut being screwed up to draw the two halves d₃ together and against the end of said cap. A handle d₅ is pinned to the other end 20 of shaft d₄ to effect rotation thereof as desired.

It will be apparent from Fig. 3 that rotation of the shaft d₄ will move the whole telescope supporting mechanism about the axis of the shaft e₁; and the cross bore of the shaft C₁ is provided 25 with a slot 15' wide enough to permit rotation of the gear E'' about the axis of the worm e₁₁ as well as longitudinally thereof. The slot 16 in the lower half of the cross part of shaft C₁ need only be wide enough to receive the gear e₇ since this 30 gear e₇ does not rotate around the axis of the worm e₁₁.

The opposite sides of the periphery of the ring D are rabbeted to receive the ends of two calotte-shaped covers d₁ and d₂, (see Fig. 2) and the 35 worm gear shaft e₁ extends through bearings 17 and 18 formed therein. A cap e₈ is pinned to one end of the shaft e₁ and is adapted to rotate and slide on a hollow cylindrical extension 19 projecting radially from the cover d₁.

40 At the other end of shaft e₁, a second cap e₉ is rotatably mounted on the shaft e₁ between the washers 20 and 21 which are pinned to said shaft e₁. The cap e₉ is screw-threaded onto the cylindrical extension 22 projecting from the cover d₂; and is adapted by rotation to move the shaft e₁ axially in its bearings to cause the worm e₁₁ to 45 operate as a rack on the gears e₇ and E''.

The two covers d₁ and d₂ are held in the rabbets of the rings D and D₂ by means of the compression spring 23 which surrounds the shaft e₁ in the hollow extension 19, and abuts against the inner end of cap e₈ and a spring washer 24 surrounding shaft e₁ at the bottom of the extension 19. The upper ends of the two covers d₁ and d₂ 55 are flattened to form a seat for the bearing member d₃ (Fig. 2a). The covers, of course, rotate in the rabbets on rings D and D₂ with the bearing member D₃ and the sight standard T whenever the shaft d₄ is turned to adjust the sight standard 60 about the axis of the shaft e₁, which is always parallel to the axis of the gun barrel.

From the disclosure, so far, it will be obvious (see Figs. 2 and 3), that rotation of the worm e₁₁ by the cap e₈ will cause rotation of the gears E'' 65 and e₇ in opposite directions. The rotation of gear E'' causes the sight standard T to tilt downwardly about the axis of shaft d₄ toward the trunnion axis; but the gear e₇, rotating in the opposite direction, causes the gear a₅ to rotate the hollow shaft a₁ in the opposite direction and this rotates the whole mechanism in the covers d₁ and d₂ bodily in the opposite direction to prevent 70 downward tilt of the sight and keep it aimed on the target, (so far as elevation of the sight is concerned). Since the shaft e₁ extends through the

cross bore of the shaft C₁, (Fig. 2), it is obvious that the shaft C₁ will be tilted through the angle of elevation from the horizontal and will be parallel to the bore axis of the gun when the latter is elevated, (see Fig. 2a). Obviously, too, the sight pointer C, with the adjustable stop plate C₃ will be tilted back through the same angle of elevation in position to contact with the stop b₂₂ when the gun is elevated by operating the elevating rack H by gear H₁.

Exactly the same movement of the several parts is effected when the cap e₉ is operated, and the worm e₁₁ acts as a rack on the gears E'' and e₇: This cap e₉ may be used to give an elevation correction in addition to that already set up by the cap e₈. The cap e₉ is provided with a scale M₄ for indicating such correction elevation against an index.

Two scale disks d₆ and d₆₆ are rotatably mounted on the worm shaft e₁ to rotate relative to indicating edges 25 and 26 respectively of sight openings 27 and 28 formed in the covers d₁ and d₂ respectively. The disk d₆ is provided with 95 graduations readable against edge 25 for use in aiming at surface targets; while the graduations 100 on the other disk d₆₆ are designed for use against aerial targets.

The disk d₆ is rotated relative to the cover d₂ by a spur gear e₂ keyed on shaft e₁ and meshing with a gear e₃ rotatable on one end 29 of a shaft 105 30 which is journaled in two bearing plates 31 and 32 (see Fig. 4a) which are pivoted by bosses 33 and 34 on the lateral extension 35 and 36 respectively of the shaft C₁.

A gear e₄ rotated by gear e₃ meshes with a gear 110 e₅ rotatably mounted on a stub shaft e₅₅, fixed to the bearing plate 32 and this gear e₅ meshes with the internal gear teeth 37 on the inner edge of the disk d₆ and rotates the disk d₆ relative to the cover against the resistance of the coil spring 115 f_h, one end of which is secured by pin 38 to the disk d₆ while the other end is secured by the pin 39 to the cover d₂.

The other disk d₆₆ is rotated by gearing similar to that just described for the rotation of disk d₆, 120 and the corresponding gears are similarly numbered. The disk d₆₆ has one end of the coil spring f_v connected thereto by a pin 40 while the other end is connected to the cover d₁ by a pin 41.

The coil springs act in opposite directions, 125 through the gearing, on the shaft e₁, and are of such strength that the friction of the gearing alone is sufficient to prevent rotation of the shaft in one direction or the other by the action of the springs alone. Even in the most unfavorable 130 case, the differences between the forces of the two springs tending to turn the shaft e₁ in one direction or the other is less than the frictional resistance on the worm gearing and the action of the springs is therefore not capable of turning 135 the shaft e₁. In the case of the average angle of elevation the turning moments from the forces of the two springs are about equal, and because of their opposite directions of rotation, are neutralized so far as turning the worm shaft e₁ is 140 concerned.

The shaft C₁ is provided with an arcuate slot 42 (see Figs. 3 and 4a) to permit the planetary swinging of the shaft 30 along with the disks d₆ and d₆₆.

As previously described rotation of the shaft d₄ (Fig. 3) rotates the sight standard T about the axis of shaft e₁ to compensate for the inclination of the gun trunnions to the horizontal. The standard T may also be displaced from the vertical 150

to correct for lateral deviation or drift of the projectile.

To effect this adjustment, the tangent scale member E is provided with a shaft e10 on which 5 the telescope carrier E1 is mounted to rock. The rocking adjustment is effected by the rotation of a small screw threaded shaft e11 to adjust the wedge nut 43a thereon against the inclined surface 43 on member E. A compression spring e12 10 on the opposite side of rock shaft e10 holds the nut 43a constantly against the inclined surface 43 of the member E.

To compensate for the displacement of the target relative to the gun during the time of 15 flight of the shell, the telescope turntable E2 is rotatably and detachably mounted by a bayonet joint connection (not shown), in the upper end of the carrier E1 and a worm e14 (see Fig. 2), engages the worm gear 44 on the lower edge of 20 the turntable E2 to rotate the latter.

The rotation of the shaft of the worm gear e14 (see Fig. 5) is transmitted by a flexible shaft C7 to a worm (not shown) in the worm casing C4 and thereby imparts the rotation of the worm 25 e14 to the worm gear ring C5 for rotating the worm shaft C2 on which a worm C22 (see Fig. 4) is fixed to mesh with worm teeth 45 on an arcuate slide member 45a mounted to slide in correspondingly curved grooves 46 in an enlargement 47 at 30 the top of the sight shaft C. The stop plate C3 projects laterally from this member 45 into the path of the stop b22 extending from the link b2.

From the foregoing description it is believed 35 that the operation of the several parts of the invention will be obvious to persons skilled in the art and need not be detailed again. It will be sufficient to state that when the gun is elevated by the gearing H and H₁, until the pointer M coincides with the pointer M₂ on the sight 40 controlled arm C, the stop plate C3 acting on stop b22 will cause the linkage to swing the pointer B₂ to one side or the other of the index B₂ on the gun cradle.

Proper setting of the gun in train thereafter 45 merely requires operation of the gear S to swing the gun about its pivot axis y—y' until the index B₃ registers with the pointer E₂.

When using the pointer sighting device with 50 guns capable of swinging about two axes, the horizontal parallelogram system of arms and levers 6—8—10—11 which adjusts the lateral pointer B₂ is of course omitted and the bell crank lever b₃ is then constructed so as to act as a pointer as shown in Figs. 6 and 7 and when following the target with the line of sight by turning the handwheel of the slewing mechanism, the lever arm E₁ constructed so as to form a counterpointer is always held so that the marks M₅—M₆ are covered.

60 The laying principles of the invention and the transmission of the laying elements can be adopted for all laying methods and consequently the sighting device may be used for all types of guns.

65 We claim:

1. A gun carriage adapted to be rotated about a train axis, a cradle mounted in said carriage to rotate about an elevation axis perpendicular to said train axis, a gun mounted in said cradle to rotate with said elevation axis and about a third axis perpendicular to said elevation axis and having an index thereon, an indicator coacting with said index and rotatable on said cradle about said third axis, a 70 sight arm mounted on said carriage to rotate 75

about an axis parallel to said elevation axis, an arm fixed to the gun trunnion and extending radially therefrom, a link pivotally connecting said arms at pivot axes equi-distantly spaced from said elevation and sight arms axes, and 80 parallel linkage mechanism connected to the free ends of said arms to rotate said indicator relative to said index.

2. A gun carriage rotatable about a train axis, a cradle rotatable in said carriage about an 85 elevation axis perpendicular to said train axis, a gun rotatable in said cradle about a third axis perpendicular to said elevation axis and having an index thereon, an indicator coacting with 90 said index and rotatable on said cradle about said third axis, a support fixed to said gun carriage, a shaft rotatable in said support about an axis parallel to said elevation axis, and sighting apparatus and linkages associated therewith to rotate said indicator.

95 3. A gun carriage, a cradle rotatable on said carriage about a gun elevation axis, a gun sleeve rotatable in said cradle about an axis perpendicular to the elevation axis, an index fixed to said sleeve, an indicator coacting with said index and rotatable on said cradle about the second named axis, a support fixed to said carriage, a hollow shaft rotatable on said support, an arm fixed to a trunnion of said cradle and extending radially therefrom, a pointer arm rotatably mounted on said hollow shaft, a link pivotally connecting said arms to maintain the pointer arm in constant parallelism with the trunnion arm, sighting scale mechanism rotatably mounted on said hollow shaft and including 100 a second pointer shaft rotatable in said hollow shaft, a sight pointer fixed radially to the end of said pointer shaft and having a stop adjustable on the free end thereof, and parallel linkage mechanism pivotally connected to said 105 indicator and to said arms and operable by engagement with said stop to move said indicator relative to said index.

4. A gun carriage adapted to be rotated about a train axis, a cradle mounted in said carriage 110 to rotate about an elevation axis perpendicular to said train axis, a gun mounted in said cradle to rotate with said elevation axis and about a third axis perpendicular to said elevation axis and having an index thereon, an indicator coacting with said index and rotatable 115 on said cradle about said third axis, an arm fixed to and extending radially from the gun trunnion, a pointer arm mounted on said carriage to rotate about an axis parallel to said trunnion, 120 a link connecting said arms to maintain the pointer arm parallel to the first named arm, a rod pivoted to the free end of said pointer arm to rotate about an axis perpendicular to the last named axis, a stop mounted to rotate about 125 the axis of said pointer arm and adjustable in the path of movement of the free end of said rod, and a linkage pivotally connected to said indicator and rod and to the free end of the first named arm and operable by contact with 130 said stop to move said indicator relative to said index.

5. A gun carriage, a gun rotated thereon about an elevation axis, a support fixed to said carriage, a hollow shaft parallel to said axis and 135 rotatable on said support, an indicator casing rotatable about the axis of said shaft, a sight rotatable on said casing about an axis parallel to said shaft and about an axis perpendicular thereto, a second shaft rotatable in said hollow 140

shaft, a worm journaled in said second shaft and said casing to rotate about the last named axis, a pointer radially fixed to said second shaft, gearing in said casing operated by said worm 5 to rotate the casing on said shaft and the sight on said casing in opposite directions, an indicator rotatable on said hollow shaft, and means connecting the gun to said indicator to move the latter relative to the free end of said pointer, 10 the gun bore being parallel to the axis of said worm when the indicator contacts with said pointer.

6. A gun carriage, a cradle mounted on said carriage to rotate about a gun elevation axis, a

15

support fixed to said carriage, a sight rotatable on said support about axes perpendicular to each other, an elevation pointer movable on said support, a drift indicator pivoted on said cradle, means for simultaneously rotating said sight and elevation pointer in opposite directions, a pointer indicator rotatable relative to said pointer, and means connecting said indicators to each other and operable by elevation of the gun to rotate said pointer indicator to contact with said pointer and by such contact to operate said drift indicator.
